UNITED STATES PATENT OFFICE.

HENRY HOFFMAN, OF EAST RUTHERFORD, NEW JERSEY.

DISPLAY-FORM.

1,351,516.

Specification of Letters Patent. Patented Aug. 31, 1920.

Application filed June 7, 1920. Serial No. 386,940.

To all whom it may concern:

Be it known that I, HENRY HOFFMAN, a citizen of the United States, residing at East Rutherford, in the county of Bergen and State of New Jersey, have invented certain new and useful Improvements in Display-Forms, of which the following is a specification.

This invention relates to display forms. 10 It relates more particularly to display forms of the type commonly known as coat hangers.

One of the objects of the invention is to produce coat hangers which shall be cheap 15 to manufacture, which shall possess permanent lasting qualities and shall not be likely to need repair. Another object is to produce a coat hanger which may be folded or collapsed into small compass so as to render the same convenient for shipping or transportation. Another object is to produce a coat hanger which shall occupy very little space when folded, and to provide means to retain the same in its folded position. 25 Another object is to produce a coat hanger which shall be made in such a manner that advertising matter or other information can be readily displayed thereon. Another object is to produce a coat hanger 30 that can be quickly and safely locked in its normal or extended position without danger of its being inadvertently collapsed at inopportune moments. Other objects and features of the invention will be obvious as the description proceeds.

The invention will be readily understood from the description in connection with the accompanying drawings, in which

Figure 1 represents the device in its normal or extended position,

Fig. 2 is a side view of the device in its folded position,

Fig. 3 is a view similar to Fig. 2, showing the opposite side of the device,

Fig. 4 is a view showing one of the details, and

Fig. 5 is a section taken along the line 5—5 of Fig. 1.

In the drawings, reference characters 1 and 2 represent two similar members, preferably made of thin strips of sheet steel, and each provided at its upper end with a hole 3. A hook 4 has its lower end bent at right angles and projects through the

holes 3 with its end upset as shown at 5, 55 thereby providing a pivot for the members 1 and 2. The members 1 and 2 have their upper edges bent at an angle to the main body portion of the members for a short distance from their lower ends as shown at 60 6 and 7. The bent portions 6 and 7 extend from the lower corners of the members 1 and 2 to the points 8 and 9, a short distance from the end, for the purpose of providing flat surfaces for sustaining the weight of 65 the garments that are hung thereupon, and also to provide a somewhat angular or curved outline for the members 1 and 2 so as to make the same fit into the shoulders, for example, of coats that may be 70 hung upon the same.

Thin strips of metal 10 and 11, preferably of sheet steel, are pivoted at the points 12 and 13 to the members 1 and 2, and are pivoted to each other at their other ends, 75 as shown at 14. The member 10 is provided at its outer end with a lip 16 which projects into the path of the member 11. The member 11 is provided with a notch 15 along its upper edge in which the lip 16 80 rests when the members are in their aligned or extended position. The parts may be so arranged that the pivot 14 is on a line with or slightly below the pivots 12 and 13, when the device is in its extended position. In 85 order to prevent the device from collapsing accidentally, locking means for the members 10 and 11 are provided. As shown in the drawings, this locking means consists of a bead or projection 17, which may be 90 made by slightly indenting the member 10 as shown in Fig. 5, and a depression or hole 18 in the member 11 into which hole or depression the projection 17 snaps when the device is extended into its normal position. 95

The hook 4 is made of springy metal so that when the device is collapsed as shown in Figs. 2 and 3, the bent portion of the hook may be passed around the opposite side of the device from its main body portion so as to retain the same in its collapsed position.

The operation of the device will be obvious. By merely turning the hook 4 from its position as shown in Fig. 2, and pulling 105 down upon the members 10 and 11, the device will be locked in its extended position. and by merely pressing upward near the

pivot 14, the device will be collapsed and can be retained in its collapsed position by turning the hook 4 as indicated in Fig. 2.

By making the device of thin flat strips, 5 it is obvious that it will occupy an exceedingly small space when collapsed. In fact, it may be slipped into the pocket and carried without discomfort, as the greatest dimension in a direction perpendicular to 10 the sheet in Fig. 1 is the bent-over portion 6, as shown in Fig. 4, which may be only a fraction of an inch. Also by using flat strips, advertising matter or other information may be stamped or printed or otherwise 15 attached to the device. The members 10 and 11 with the lip 16 and the locking

means provides a support upon which trousers or other garments may be safely hung.

I claim:

In a device of the class described, a pair 20 of hinged members each consisting of a flat strip of metal having its edge bent at an angle to the main body portion at one end thereof, a second pair of members made of flat strips of metal hinged to each other and 25 to said first pair, locking means for retaining said second pair in alined position and a hook adapted to support said device in the open position and to retain it in its closed position. 30

In testimony whereof I affix my signature.

HENRY HOFFMAN.
